UNITED STATES PATENT OFFICE.

WHITMAN SYMMES, OF SAN FRANCISCO, CALIFORNIA.

ELECTRIC-FIXTURE SUPPORT.

Application filed October 23, 1922. Serial No. 596,321.

The invention relates to electric lighting fixture supports and particularly to a support for side brackets or other wall fixtures.

For some time it has been considered desirable to provide detachable electric lighting fixtures, so that fixtures of one design may be readily replaced by fixtures of another design and so that a tenant may acquire his own fixtures and take them with him when he vacates his tenancy. These fixture supports should be of such construction that they accommodate themselves to the standard appliances employed for wiring houses and providing outlets and so that the fixtures may be attached and detached by the housewife, without the aid of any tools. They must further be fool proof and accident proof and must conform to the standards and regulations adapted by controlling organizations, such as the National Board of Fire Underwriters. As far as I am aware, no fixture support, has as yet been provided which satisfies all of these conditions.

It is an object of the present invention, therefore, to provide a detachable fixture construction which meets all of these requirements.

Another object of the invention is to provide a detachable fixture which is simple and sturdy in construction and which may be employed in connection with the various standard forms of outlet boxes or junction boxes employed by electricians.

The invention possesses other advantageous features, some of which, with the foregoing, will be set forth at length in the following description, where I shall outline in full, that form of the invention which I have selected for illustration in the drawings accompanying and forming part of the present specification. In said drawings I have shown several embodiments of my invention, but it is to be understood that I do not limit myself to the forms shown, since the invention, as set forth in the claims, may be embodied in a plurality of other forms.

Referring to said drawings:—

Figure 1 is a vertical section through a wall fixture back plate embodying the features of my invention.

Fig. 2 is a vertical section through an outlet receptacle embodying the features of my invention.

Fig. 3 is a front elevation of a portion of

an outlet box embodying one of the features of my invention.

Fig. 4 is a section taken on the line 4—4, Fig. 2.

Fig. 5 is a section taken on the line 5—5, Fig. 3.

Fig. 6 is a perspective view of the parts of the attaching structure in separated positions.

Fig. 7 is a vertical section through an outlet box provided with the standard plaster ring and embodying my invention.

Fig. 8 is a vertical section through an outlet box provided with a plaster ring of my invention.

Fig. 9 is a side elevation of a bell back plate showing the method of arranging the attaching structure thereon.

Fig. 10 is a side elevation of a deep bell back plate showing the method of arranging the attaching structure thereon.

Fig. 11 is a front elevation of an electrical receptacle plate, which may be employed with a plaster ring of my invention.

Fig. 12 is a front elevation of a plaster ring of my invention.

Fig. 13 is a front elevation of an outlet box provided with a standard plaster ring.

Fig. 14 is a front elevation of a receptacle plate adapted to be used with the outlet box shown in Fig. 13.

Fig. 15 is a perspective view of the attaching structure mounted on a bracket back.

Fig. 16 is a perspective view of one form of receptacle plate.

Fig. 17 is a rear view of the receptacle plate showing the receptacle with the cover removed.

In accordance with my invention I provide a removable bracket lighting fixture which may be attached to the wall receptacle by mere insertion without the aid of any tools, and which, when in place, is securely held in position, so that it may not be accidentally dislodged by a person moving about or cleaning up the room or manipulating the fixture. The attaching structure is constructed so that the fixture is supported independently of the electrical connections, so that the socket or electrical receptacle and the plug are not subject to any supporting strain. The component parts of the attaching structure are arranged and disposed in such manner that the structure is

applicable to the standard outlet boxes now universally employed, so that it may be installed in old houses with the minimum of effort and so that it may be included in new work without requiring the use of special outlet boxes. This feature is of the greatest importance, since the expense involved in discarding old standards and establishing new standards is a great economic waste which is not tolerable. Removable lighting fixtures may be proposed, but unless they conform to established standards they are impractical and practically inoperative, since their use would not be tolerated. I have produced a structure which meets all of the requirements and conforms to all of the standard specifications and at the same time is simple, rugged and inexpensive.

The device of my invention comprises two major parts, one of which, constituting the receptacle, is arranged in or secured to the wall of the room or building so that it remains permanently in place. The other major part constituting the plug is arranged on or secured to the back of the lighting fixture. The receptacle constitutes a support for the fixture and electrical contacts to which the service wires are connected. The plug constitutes a support engaging element and electric contacts or fingers for engagement with the contacts in the receptacle.

Present electrical wiring specifications require the use of a metallic outlet box in the wall, into which the service wires extend. The electrician in wiring the house, carries his wires into the outlet box and it is the function of the fixture hanger to connect these wires to the fixture and hang the fixture. Outlet boxes are made in two standard styles, with and without plaster rings, the boxes provided with plaster rings being deeper by the depth of the ring. In Figs. 2 and 3 I have shown an outlet box 5 which is not provided with a plaster ring and in Figs. 7 and 13 I have shown outlet boxes 5 provided with standard plaster rings 6. In Figs. 8 and 12 I have shown ringless outlet boxes 5 to which special plaster rings 7 of my invention are attached, usually by screws 8 passing through slots 9 in the base of the ring and through ears 12 on the periphery of the outlet box.

Overlying the wall and covering the opening of the outlet box, is a receptacle plate on which the socket or receptacle is mounted. The shape of the receptacle plate and the means for securing it in place vary with the style of outlet box employed. When a ringless outlet box is employed, such as is shown in Fig. 2, a receptacle plate 13, as shown in Figs. 2 and 16 is employed, the plate being shaped to cover the aperture in the wall. The electrical receptacle 14, is mounted substantially centrally on the

plate 13 and extends into the outlet box, so that the outer face of the plate is substantially flush with the wall. The plate is supported on the outlet box by a chair or hollow bracket 15 having tabs 16, which are secured to the back wall of the outlet box and having forwardly extending spaced legs 17 having flanges 18 on their forward ends which are engaged by screws 19 passing through the plate. The legs 17 are spread apart so that they surround and form a pocket for the receptacle 14, thus permitting the plate and its attached receptacle to be readily attached to the outlet box. The length of the legs 17 varies in accordance with the depth of the outlet box and when an outlet box with a standard plaster ring is used, as is shown in Fig. 7, the legs should be longer than when a ringless box is used.

The special plaster ring of my invention, which may be attached to a ringless outlet box, as shown in Fig. 12, or which may form an integral part of a special outlet box, standard in every particular with the exception of the construction of the plaster ring, is constructed in such manner that the receptacle plate may be readily attached thereto, thus obviating the use of the chair 15. The plaster ring 7 of my invention is provided with webs 21, flush with the outer surface of the ring, which are provided with apertures 22 for the reception of screws 23 passing through the plate. These apertures may be circular or may be elongated to permit a slight adjustment of the plate with respect to the plaster ring. The plaster ring may be slightly out of true position and by providing for adjustment, the plate may be accurately positioned.

The receptacle plate serves as a support for the applied fixture and for the electrical receptacle. The plate preferably comprises a metallic stamping having a hole or slot 25 punched therein to receive the supporting element on the fixture, the tongue 26 which is cut out in forming the slot being bent back at the angle of the supporting element on the fixture, at the top of the slot to serve as a support for the upper end of the clip 27 which forms a housing to enclose the inserted supporting element. Below the slot, the metal of the plate is bent or pressed back to form a substantially cylindrical socket 28 at the base of which the electrical receptacle 14 is disposed. Below and preferably also above the socket 28, the metal of the plate is pressed back to form lug seats 31-32, opening into the socket 28 and having inclined bottom walls 33-34, and substantially perpendicular side walls 35. The inclined walls 33-34, at their bases or bottoms are provided with integral rearwardly extending tongues 36 which are provided on their rear ends with clips 37 which are bent to lie against the rear face of the recep-

tacle, holding the receptacle firmly in place. The receptacle is provided with a peripheral shoulder 38 bearing against the rear edge of the wall of the socket 28, so that it is rigidly secured to the plate. The receptacle is also provided with longitudinal grooves 39 in its outer surface in which the tongues 36 are disposed, thus preventing rotation of the receptacle on the plate. The clip 27 is welded, brazed or otherwise secured to the plate and the wall 33 and at its lower end is provided with inturned flanges 41 which underlie the tongue 36 of the wall 33.

Embedded in the body of the receptacle, which is preferably made of hard rubber, porcelain or other electrical insulating material, and projecting rearwardly therefrom, is a screw 42, over which fits an insulating protecting cap 43, held in place by a nut on the screw. The cap covers the contacts in the receptacle and the rear end of the housing to receive the applied supporting element, and prevents the accumulation of dust on the contacts and obviates the presence of any exposed contacts. The cap and the receptacle body are provided with depressions which register to form apertures 44 through which the service wires extend to the contacts in the receptacle.

The body of the receptacle is provided with two elongated vertical slots 45 behind which are arranged the resilient contacts 46. Each contact comprises a resilient metallic clip having a flange on one end which is secured to the receptacle body by a hollow screw 47, in which is seated a headed screw 48, by which the service wire is connected to the contact. The other side of the contact clip is free to move as the contact blade is inserted or removed, so that tight frictional contact is maintained. The movable end of the contact clip is curled outwardly, as at 49, to facilitate entrance of the contact blade and this curled edge is disposed behind a shoulder 51 at the side of the slot 45, so that the entering blade is directed into the clip and cannot strike and distort the end of the clip. The slots 45 and the contact clips 46 are longer vertically, than the vertical dimension of the contact blade, for reasons which will hereinafter appear.

The fixture supporting member and the electric connecting plug are carried by the fixture, so that when the fixture is applied, the circuit to the lamp socket carried by the fixture is completed and when the fixture is removed, the circuit is broken. When the invention is applied to a bracket fixture having a slightly recessed back 52, as shown in Figs. 1 and 15, a metallic strap or plate 53 is attached to the back by screws 54, the lower screw being countersunk so that its head lies flush with the surface of the strap. At its upper end the strap is provided with an integral downwardly inclined tongue or

peg 55 which constitutes the fixture supporting element. This tongue fits into the slot 25 in the receptacle plate and its inclined position necessitates that the fixture be moved inwardly and downwardly as it is applied and conversely, as it is removed. The weight of the fixture, or any applied weight, causes it to seat more firmly on the plate and due to the necessary upward movement of the fixture, to effect its removal, accidental dislodgment of the fixture is a remote possibility. By providing an elongated slot 25 and a supporting tongue of similar cross section, a large supporting surface is obtained and the fixture is held against rocking. To further prevent rocking of the fixture on the plate and to relieve the tongue and slot of any rocking strains, a pair of lugs 56 are struck from the strap 53 at such position, that they lie within the lower lug seat 32 and contact with the side walls thereof. These lugs 56, other than positioning the fixture on the plate, also serve to hold the body 57 of the plug in position on the strap. The body of the plug is made of some suitable insulating material and is held to the strap by the screw 58. Interposed between the plug body and the strap is a disc 59, preferably formed of fiber, which is provided with two apertures 61 through which the insulated wires on the fixture extend to the contact posts 62 on the plug. This disc holds the wires down against the bracket back so that they cannot get in the way of other parts, when the fixture is to be applied. The plug is further held in position by the upper screw 54, the head of which lies in a saddle in the plug and disc and by the lugs 56, which lie on opposite sides of the projections 63 and 64 on the disc and plug. The plug is provided with contact blades 65 in which the contact posts are seated. The blades are of less width than the width of the contact clips of the receptacle so that they may move vertically in the contact clips as the fixture is applied and removed, the vertical movement being one of the component movements of the inclined movement of the fixture.

Many lighting fixture bracket back plates are not formed with slightly recessed backs to which the strap 53 may be directly attached, and when such fixtures are used, auxiliary means must be employed for attaching the strap to the fixture. In Figs. 9 and 10 I have shown brackets having back plates formed of bells or canopies provided with means for attaching the straps in place. The canopy 67, shown in Fig. 9 is provided with an annular portion 68 having a surface lying in a plane substantially perpendicular to the axis of the canopy. Secured to the canopy, by screws passing through said annular portion, and disposed within the canopy is a diametrically disposed vertical

bar 69 to which the strap 53 is attached, the bar 69 being positioned so that the plug is properly disposed with respect to the rear edge of the canopy. In Fig. 10 I have 5 shown a fixture embodying a slip canopy 71 to which it is not feasible to attach the strap. The fixture comprises a tube 72 on which the canopy is arranged. Disposed within the tube 72 and held in place therein, as 10 by a screw knob such as is shown in Fig. 9, is a short tube 73, to the rear end of which is screwed a fitting or bracket 74, to which the strap 53 is secured.

I claim:—

15 1. A detachable electric lighting fixture adapted to be applied to a receptacle plate having a recess therein and an aperture above the recess and having a receptacle secured to the plate and disposed behind the recess, comprising a lighting fixture bracket having a back, a plug secured to said back and projecting therefrom, projecting lugs adjacent the plug, said plug and lugs adapted to engage said recess and a projecting tongue on the back adapted to engage in said aperture.

20 2. A detachable electric lighting fixture adapted to be applied to a receptacle plate having an aperture and a recess spaced from the aperture, comprising a lighting fixture, a strap secured to said fixture, a projecting tongue and projecting lugs integral with said strap and a plug secured to the strap, said tongue being arranged to seat in the aperture and said plug and lugs being 25 arranged to seat in the recess.

30 3. A detachable electric lighting fixture adapted to be applied to a receptacle plate having an aperture and a recess spaced from the aperture, comprising a lighting fixture, a strap secured to said fixture, a projecting tongue and projecting lugs integral with said strap, a plug secured to said strap, an

extension on said plug disposed between said lugs, said tongue being arranged to seat in 45 the aperture and said plug and lugs and extension being arranged to seat in the recess.

4. A detachable electric lighting fixture adapted to be applied to a receptacle plate having an aperture and a recess spaced from 50 the aperture, comprising a lighting fixture, a strap secured to said fixture, an integral, downwardly inclined tongue on said strap, integral lugs on said strap and a plug secured to said strap and engaging said lugs, 55 said tongue being arranged to seat in said aperture and said lugs and plug being arranged to seat in said recess.

5. The combination, in a detachable electric lighting fixture, of a lighting fixture, a 60 strap secured thereto, an integral tongue on said strap, integral lugs on said strap, a plug secured to said strap and engaging said lugs and a disc interposed between the plug and the strap provided with apertures 65 through which the fixture wires are passed.

6. The combination with a lighting fixture, of a strap secured thereto, said strap being bent downward at its upper end to 70 form an inclined projecting tongue, lugs on said strap, a plug attached to said strap and an extension on said plug disposed between said lugs.

7. The combination with a lighting fixture, of a strap secured thereto, a downwardly inclined projecting tongue at the upper 75 end of said strap, a plug secured to said strap below said tongue, a projection on said plug, upwardly inclined lugs extending from said strap on opposite sides of said projection and contact blades extending from said plug.

In testimony whereof, I have hereunto set my hand.

WHITMAN SYMMES.
